ROLLER MOUNTING

Adelbert M. Graham, Beverly Hills, Calif., assignor to Walter G. L. Smith, Los Angeles, Calif.

Application July 31, 1939, Serial No. 287,599

9 Claims. (Cl. 308—18)

This invention relates to a pulley or roller mounting. It is disclosed in connection with a floating cable guide adapted to prevent lateral swaying of a cable line between a hoisting drum of the draw-works of a well drilling rig and the crown block at the top of the derrick. It is, however, as will be readily apparent, adaptable for use in many installations of other kinds.

In a cable guide of the type just mentioned, two outside pairs of cable rollers with parallel axes and two central rollers with their axes perpendicular to those of the four outside rollers are mounted in a frame structure which is suspended at an elevation inconvenient of access by the workers. It is therefore an advantage to have a cable guide of this type so constructed that it will operate for a long period of time without attention for lubrication or adjustment of the bearings, or tightening of the means by which the several members of the structure are held in assembled relationship.

It is an object of this invention to provide a roller mounting which will require a minimum of attention for lubrication.

It is also an object of this invention to provide a roller mounting which will require a minimum of attention for adjustment of the roller bearings or tightening of the several means by which the mounting is held in assembled relationship.

Further objects and advantages of the invention will be made evident throughout the following part of the specification.

Referring to the drawing, which is for illustrative purposes only,

Fig. 1 is a perspective view of a floating cable guide for a well drilling rig, of the kind to which this invention is applicable.

Fig. 2 is an elevational view of one roller and its mounting shown partly in section.

Fig. 3 is an end elevation of a roller and its mounting.

In Fig. 1 is shown a cable guide 11 engaging a cable 12 extending from a drum (not shown) of the draw-works of a well drilling rig to a crown block (not shown) at the top of the derrick. The guide 11 is suspended in position by means of a pair of cables 13 secured at their upper ends to a suitable part of the derrick so that it is at a substantial height above the cable drum and the floor of the derrick and relatively inaccessible to the operators of the rig. The guide 11 is controlled in its movement horizon-

tally by means of two cables 14 which are arranged parallel to the axis of the drum, and each of which passes over a pulley (not shown) and downwardly to a counterweighted end, all 5 in the manner shown and described in a co-pending application of Walter G. L. Smith, the assignee of the present application, Serial No. 118,979, filed January 4, 1937.

The cable guide 11 comprises two frame members 15 journaling upper and lower pairs of relatively spaced rollers 16 and 17 and an intermediate pair of relatively spaced rollers 18 disposed perpendicularly to the upper and lower pairs of rollers, so that when the cable 12 is extended between the relatively spaced upper and lower pairs of rollers and the relatively spaced intermediate pair of rollers it is engaged on all four sides. The frame members 15 are 10 held in spaced relation by rods or shafts 19 which also serve as journaling members for the relatively spaced pairs of rollers 16 and 17. Formed in each of the frame members 15 is a central arched wall 20, and extending across each side 15 of this arched wall and connecting its ends are parallel walls 21 between which one of the intermediate rollers 18 is journalled on a rod or shaft 19', the outer face of the roller conforming to the wall 20. A central portion 22 of the arched 20 wall 20 is provided with a projecting ear 23 which serves as a means for connection of the cables 13 and 14.

Each one of the frame members 15, which is 25 of a generally rectangular configuration, is formed at each one of its four corners with a vertically arranged, open-ended slot 24 extending from the upper or lower edge of the frame member, as the case may be, inwardly toward the central portion of the frame member. Each of 30 the walls 21 is formed with a similar open-ended slot 24' disposed horizontally and extending laterally from the inner edge of the wall 21 a portion of the distance across it. Each of the rods or shafts 19 is seated in a pair of aligned slots 24 and each of the shafts 19' is seated in a pair of aligned slots 24'. As each of the six rollers 16, 17, and 18 is mounted on its shaft 19 or 19', and each of these shafts is seated in one pair of 35 aligned slots 24 or 24', in the same manner as any one of the other five rollers and by means of similarly constructed and assembled structural elements, the following description will suffice for all six of the rollers and their 40 mountings.

The roller 16 as shown in the drawing comprises a cylindrical metal frame member 25 and a rubber body 26. Other types of rollers or pulleys may be used to meet the conditions of other installations without departing from the spirit of this invention. A bore chamber 27 of the cylindrical frame member 25 has two central chambers 28, each in the shape of a frustum of a cone, communicating at their smaller ends at the median point of the bore at 29. The bore chamber 27 also has an outer cylindrical chamber 30 at each of the ends of the roller frame 25 which communicates with the larger end of the adjacent conical chamber 28, providing at the junction point an annular shoulder 31 by reason of the larger diameter of the chamber 30.

In each of the cylindrical chambers 30 is seated a ball bearing 32 which abuts the shoulder 31 at its inner end and is disposed with its outer race 33 and its inner race 34 in tight fitting engagement with the bore chambers 30 and the shaft 19 respectively in the usual manner of ball bearing assemblies. The inner race 34 of the ball bearing 32 abuts endwise a shoulder 35 on the shaft 19. The bearing 32 is fixed longitudinally upon the shaft 19 between the shoulder 35 and a jamb nut 37 which is threaded upon the shaft. An annular ball chamber 38 of the ball bearing is closed at its longitudinally outer end by means of a sealing ring 39 secured to the outer race 33 and slidably fitting the inner race 34. Lubricant placed in the central bore chambers 28 when the roller structure is assembled is propelled by centrifugal force into one of the ball chambers 38 through the peripheral portion of the inner open end 40 of the chamber 38 and flows back into the chamber 28 through the central portion of the opening 40, providing a circulation which insures an adequate supply of clean fresh oil at all times to the operative surfaces of the bearing.

This circulation is explained as follows: The rotative velocity of oil in the bearing chamber 38 is less than that of oil in the chamber 28 at the same radial distance from the axis of the rod 19, due to frictional contact with the bearing balls which rotate at half the speed of the roller frame 25 and outer race 33, and with the inner race 34 which is stationary. Consequently, the centrifugal force applied to oil in the bearing chamber 38 and the fluid pressure resulting is also less. This difference in pressure between oil at corresponding radial positions is increased when the balls are mounted in a cage, which has the effect of further retardation of the rotative velocity of the oil in the bearing chamber. It is also true that the pressure differential between oil at the peripheral portion of the open inner end 40 of the bearing chamber 38 and oil at the centermost portion thereof is greater than the pressure differential between oil at two corresponding radial positions in the chamber 28.

As a result of this pressure relationship, oil flows from the chamber 28 into the radially outer portion of the chamber 38 and along the outer surface of the ball cage if there be one, where the fluid pressure is less, passes to the outer end of the chamber 38, flows centrally thereof along the inner surface of the ball cage, and leaves the chamber at the central portion of its inner end.

While this circulation of oil would occur if the chamber 28 were cylindrical, its conical shape possesses two advantages. It provides a smoother circulatory route in which eddy currents and other retarding influences are less apt to be

present, and for any given capacity of the chamber 28 circulatory contact is maintained with the peripheral and centermost portions of the end 40 of the chamber 38 for a longer period as the quantity of oil in the chamber 28 decreases due to leakage.

The inner end of the slot 24 is counterbored at 41 inwardly from the outer face 42 of the frame member 15. An annular ring or washer 43 is seated within this counterbore and is free to rotate with respect to the shaft 19. The inner face 44 of the frame member 15, which may, if desired, be provided with an integral inwardly extending spacing boss 45, is spaced from the bearing 32 and the end plane of the roller 16 by the nut 37 and a lock nut 46. The frame member 15 is held against movement away from the roller 16 by means of a nut 47 screwed on the outer threaded portion of the shaft 19 and bearing 20 against the outer face of the washer 43. A cotter pin 48 is placed in the outer end of the shaft 19 and is spaced along the shaft from the outer face of the nut 47 a distance less than the depth of the counterbore 41.

If, after the rollers have been assembled in the frame members 15 and the cable guide has been placed in its relatively inaccessible position, any one of the nuts 47 becomes loose upon the threads of its shaft 19, the washer 43 will 25 prevent the shaft from moving outwardly in its slotted seat 24 and possibly becoming entirely disengaged from the frame members 15. Before a nut 47 should it thus become loosened, can back off on its shaft 19, a sufficient distance for 30 the washer 43 to clear the outer faces of the frame members, thereby allowing disengagement of the shaft from the frame members, it will be stopped by the cotter pin 48. Also, should the nut 47 become loosened on its threads and the 35 locknut 46 and the nut 37 as a result thereof also become loosened and move outwardly on the shaft 19, the bearing 32, even though it has limited lateral play, will still remain in operative position by reason of the length of the cylindrical bore portion 30 which extends beyond the outer face of the ball bearing. It will thus be 40 evident that even though one of the nuts 47 should become loosened upon its threads, the rollers will yet be held in proper position and will 45 continue to function as intended, and the circulation of the lubricant through the bearings will 50 not be interrupted.

While this invention has been shown and described for purposes of illustration and explanation in connection with an installation of one specific kind, it is apparent that a roller or pulley mounting constructed in accordance with this invention may be employed in many other fields of use.

I claim as my invention:

1. In a pulley mounting, the combination of: a frame member having an open-ended slot therein, said slot being counterbored partway through said frame member at its inner end to a larger diameter than the width of said slot; a rod snugly seated in the inner end of said slot; an end thrust element longitudinally securable on said rod and bearing against the side of said frame opposite said counterbore; a washer on said rod snugly seated in said counterbore; and clamping means secured on said rod adjacent the counterbored side of said frame, said means bearing laterally upon said washer, and being adapted to clamp said frame member pressurally between said washer and said element.

2. In a pulley mounting, the combination of: a frame arm formed with an open-ended slot therein, said slot being counterbored partway through said frame arm at its inner end to a larger diameter than the width of said slot; a shaft snugly seated in said slot having a threaded portion adjacent the counterbored side of said frame arm; an end thrust element longitudinally securable on said shaft and bearing against the side of said frame arm opposite said counterbore; a washer on said rod snugly seated in said counterbore; a nut threaded upon said threaded portion of said shaft and bearing against the outer face of said washer; and a travel stop for said nut removably fastened on said shaft beyond and spaced from said nut a distance less than the depth of said counterbore, said nut being free to turn with respect to said cotter pin.

3. In a pulley mounting, the combination of: two frame arms each formed with an open-ended slot therein and formed with a countersunk recess in its outer face adjacent the inner end of said slot and extending partway through the frame arm; a shaft with threaded end portions, said shaft being seated in said slots; a rotating element journaled on said shaft; a first set of two nuts on said shaft one at each end of said element for preventing longitudinal displacement of said element; a washer on said rod snugly fitting within each of said recesses; a second set of two nuts threaded one upon each end of said shaft and bearing against the outer face of a corresponding one of said washers and being adapted to clamp a corresponding one of said frame arms pressurally between the corresponding washer and the corresponding first nut; a travel stop for each nut of said second set removably fastened on said shaft adjacent each of its ends and spaced from the end of said nut of said second set a distance less than the depth of said recess; and means for positioning said frame arms with said slots aligned with each other.

4. In a pulley mounting, the combination of: two frame arms each formed with an open-ended slot therein, said slots being counterbored adjacent their inner ends partway through said respective frame arms to a larger diameter than the width of said slots; means securing together said arms with said slots aligned and their counterbores facing outwardly; a shaft seated in said slots, said shaft having threaded end portions; a rotating element journaled on said shaft; spacer means on said shaft between each of said arms and said element; a washer on said rod snugly fitting within each of said counterbores; a nut threaded upon each end of said shaft and bearing against the outer face of a corresponding one of said washers and being adapted to clamp a corresponding one of said frame arms pressurally between the corresponding washer and spacer means; and a travel stop for each of said nuts removably fastened on said shaft beyond and spaced from said respective nuts a distance less than the depth of said counterbore.

5. In a pulley mounting, the combination of: two parallel frame members, each formed with four outwardly directed, open-ended, symmetrically disposed slots, and each counterbored on its outer face at the inner ends of said slots partway through said frame member to a diameter greater than the width of said slots, each slot being in registering alignment with a corresponding slot of the other frame to constitute a pair; a

5 shaft seated in each pair of said slots, said shaft having threaded end portions; a roller mounted on each shaft between said frames; jamb nuts on each of said shafts between said roller and each of said frames; a washer snugly seated on each of said rods in each of said counterbores; a second nut on said shaft outside of each of said frames and bearing on said washer and being adapted to clamp a corresponding one of said frame members between a corresponding one of said washers and a corresponding one of said jamb nuts; and a cotter pin in each of said shafts beyond said second nut and spaced therefrom a distance less than the depth of said counterbore, said last-named nut being free to turn with respect to said cotter pin.

6. In a pulley mounting, the combination of: a frame member having an open-ended slot and a counterbored recess on one side of said frame member disposed along said slot; a shaft longitudinally movably seated in said slot and laterally restrained by the side walls of said slot; a nut on said shaft bearing against the other side of said frame member; means including the pulley and its shaft bearings for preventing movement of said nut away from said frame member; a washer sleeved on said shaft and seated in said recess and bearing against the inner end wall of said recess; a second nut on said shaft bearing against said washer; and a travel stop means for said second nut removably secured to said shaft for preventing travel of said nut a sufficient distance to allow said washer to become unseated from said recess.

35 7. In a pulley mounting, the combination of: a rod; a slotted frame member, the slot of which is adapted to receive said rod through the open end of said slot by a lateral movement of said rod from without said frame member and to afford a seat for said rod transverse said frame member in which lateral movement of said rod is prevented except toward said open end; a recess extending part way into said frame member from a first surface of said frame member which is intersected by one open side of said slot, said recess opening into said slot between said rod and said open end and extending laterally beyond the walls of said slot; a retainer key-seated in said recess and disposed across said slot outwardly from beyond said rod for preventing movement of said rod toward said open end; an end thrust element secured on said rod to bear against a second surface of said frame member which is intersected by the other open side of said slot; and clamping means mounted on said rod and bearing against said retainer for forcing said frame member against said end thrust element.

60 8. In a pulley mounting, the combination of: a shaft support having an open-ended slot formed therein; a stationary shaft seated between and in engagement with the side walls of said slot; and means for preventing movement of said shaft toward said open end of said slot comprising a member sleeved on said shaft and wider than said slot, said support being provided with a shoulder means disposed at a substantial angle to the direction of said movement toward said open end of said slot and engaging said member in a manner to prevent movement of said member toward said open end.

65 9. In a pulley mounting for installation in an apparatus at a location inaccessible for adjustment, the combination of: a stationary shaft; a wheel; means for rotatably mounting said

wheel on said shaft including a pair of cylindrical rolling contact bearings; stop means on said shaft and stop means on said wheel for each of said bearings, said four stop means limiting movement of said bearings toward each other along said shaft and said wheel, said wheel, shaft, and bearings defining a liquid-tight lubricant reservoir between said bearings, said wheel and shaft defining a cylindrical housing for each of said cylindrical bearings substantially longer than its corresponding bearing and in which said bearing is slidably fitted, said housing extending from its corresponding stop means in a direction away from said reservoir; a first nut threaded on said shaft on the outside of each bearing for clamping said bearing against the correspond-

ing stop means on said shaft and wheel; a supporting means in end thrust contact with each of said first nuts by which said shaft is laterally restrained and on which said shaft is longitudinally slidable; a second nut threaded on said shaft for clamping each of said supporting means against said corresponding first nut; and a travel stop for each of said second nuts, each said travel stop being removably fastened to said shaft at a point sufficiently close to its corresponding second nut to prevent movement of either bearing sufficient to project the outer end of said bearing beyond its housing upon all of said first and said second nuts becoming loosened.
